ATTORNEY

UNITED STATES PATENT OFFICE.

AUGUST WENGENROTH, OF TROY, NEW YORK.

IMITATION CHRISTMAS-TREE.

SPECIFICATION forming part of Letters Patent No. 255,902, dated April 4, 1882.
Application filed February 13, 1882. (No model.)

To all whom it may concern:

Be it known that I, AUGUST WENGENROTH, of Troy, county of Rensselaer, and State of New York, have invented certain new and useful Improvements in Imitation Christmas-Trees, of which the following is a specification.

The object of this invention is to furnish a portable imitation Christmas-tree which may be readily put up for use whenever required; and the invention consists of a Christmas-tree made of an upright trunk, to which are applied by suitable means a number of detachable branches made of wire covered with chenille, the ends of the branches having spirally-bent terminals and drip cups for the candles.

In the accompanying drawings, Figure 1 represents a side elevation of my improved imitation Christmas-tree; and Figs. 2 and 3 are respectively a detail horizontal section and a side view of the trunk, showing the method of applying the detachable branches thereto.

Similar letters of reference indicate corresponding parts.

In the drawings, A represents the trunk of my improved portable imitation Christmas-tree, and B the detachable branches of the same. The trunk is covered, in imitation of the natural color of the trunk of a pine-tree, with ground cork or similar material. The trunk A is made of one piece or of two or more sections, which may be coupled together by any approved means, according to the size of the tree. The trunk is connected in detachable manner to a suitable base-plate or support, C. The branches B gradually diminish in size from the lower part of the trunk to the upper part of the same, and are made of wire of suitable thickness, which is covered with green chenille. The inner uncovered ends of the branches B are bent into hook shape, and are inserted into eyes a, which are driven or screwed into longitudinal grooves b of the trunk, as shown clearly in Fig. 3, so that the branches are thereby firmly supported in position. By arranging the trunk with ten longitudinal grooves and applying the lowermost five branches to eyes driven into every second groove, and the next five branches to eyes driven into the intermediate grooves, and so

on alternately up to the uppermost branches, 50 the branches extend from the trunk A in a more natural manner and impart a less stiff appearance to the tree.

In place of attaching the inner ends of the branches to the trunk by the screw-eyes, any 55 other equivalent means may be employed whereby the branches B are conveniently applied to and removed from the trunk.

To the upper end of the trunk is applied an extension or top section, A', which is formed 60 of wire covered with green chenille, and which, like the twigs of the branches B, is arranged with short twigs extending therefrom, as shown in Fig. 1. The outer ends of the branches B, and, if desired, the outer ends of 65 some of the twigs, are bent into spiral shape, so as to form a kind of socket, d, for inserting the candle.

Below the sockets drip-cups e are arranged, which are placed on the ends of the branches 70 before the spiral sockets are formed.

The chenille employed for covering the branches is preferably treated with alum or other substances, which render it fire-proof.

The Christmas-tree can be conveniently 75 packed and shipped by detaching the branches and top section from the trunk, then detaching the trunk from the base and placing all the parts in a box of proper size. A Christmas-tree of this kind may be used again from 80 year to year, if properly packed and stored away, it forming a neat and convenient device whenever natural trees are not handy, or objectionable on other grounds.

Having thus described my invention, I claim 85 as new and desire to secure by Letters Patent—

1. An imitation Christmas-tree consisting of an upright trunk, detachable covered wire branches, and means whereby the branches are attached to the trunk, substantially as set forth. 90

2. An imitation Christmas-tree consisting of a trunk, detachable branches, a detachable top section, and means for attaching the branches and top section to the trunk, substantially as set forth. 95

3. In an imitation Christmas-tree, the combination of a trunk having longitudinal grooves, and eyes secured into the grooves, with covered

wire branches having bent inner ends, which are inserted into the eyes of the trunk, substantially as set forth.

4. In an imitation Christmas-tree, a branch made of wire covered with chenille, as set forth.

5. In an imitation Christmas-tree, the combination of a covered wire branch or twig with a spirally-bent terminal and a drip-cup below the same for the candle, as specified.

10. 6. In an imitation Christmas-tree, the combination of a trunk, a detachable top section, detachable branches, means for attaching the

top section and branches to the trunk, and means arranged at the ends of the top section and the branches for holding the candles, substantially as specified.

In testimony that I claim the foregoing as my invention I have signed my name in presence of two subscribing witnesses,

AUGUST WENGENROTH.
